UNITED STATES PATENT OFFICE

WILLIAM G. HULBERT, OF EASTON, PENNSYLVANIA, ASSIGNOR TO WILLIAM WHARTON, JR. & COMPANY, INCORPORATED, OF EASTON, PENNSYLVANIA, A CORPORATION OF PENNSYLVANIA

TRACK STRUCTURE

Application filed January 27, 1932. Serial No. 589,260.

It is old practice with street railways to employ special work such as frog and crossing structures, including cast iron bodies which support hard metal centers. Generally speaking up until recently this practice has been uniformly satisfactory, but the ever increasing traffic of heavy trucks and buses has changed conditions and there now is much complaint that the rails work loose and that the cast iron bodies break. The problem could be solved by employing solid manganese steel frogs or crossing structures, as in steam trackwork, but that would be too expensive and so the desideratum is to provide a rigid and strong construction that will stand up under modern conditions of heavy traffic and to do this in such way as will not appreciably enlarge the cost of the old work.

In achieving this object I integrally join intersecting continuous rails by removing the heads and enough of the proximate base flanges in the area of intersection to provide for securing them at the desired angle of intersection and then house the cut down rails in a frog or crossing structure consisting of a unit shell U-shape in cross section or of the general form of an arch whereof the roof has intersecting flangeways matching the flangeways of the rails and whereof the side walls straddle the rails and are welded to the base flanges thereof, the ends of the shell being welded to the rails.

The nature, characteristic features and scope of the invention more readily will be understood from the following description, taken in connection with the accompanying drawings, forming a part hereof, wherein

Figure 1 is a plan view of special track-work embodying the invention.

Fig. 2 is a sectional view thereof more particularly showing the manner of joining the continuous rails to each other and to the frog shell.

Fig. 3 is a section on line 3—3 of Fig. 1.

Fig. 4 is a section on line 4—4 of Fig. 1.

Fig. 5 is a section on line 5—5 of Fig. 1.

Fig. 6 is a perspective view of the shell or housing constituting the frog or crossing structure.

In pursuance of my method of providing

rigid and strong intersecting trackwork particularly adapted for street railways subject to heavy traffic, I fashion the intersecting through or continuous rails 5 and 6 so that they can be assembled at the desired angle of intersection, for instance, by removing the heads, as at 7, in the area of intersection, and by removing enough of their proximate base flanges 8. The rails then are secured as by bolts 9 passing through their webs 60, 10 and spacing blocks 11, and by metallically uniting them as by weld deposit 12 in the straight groove provided by the cutaway base flanges and by deposit metal 13 between the abutting ends of the outside flanges 14. 65

Endwise of the intersecting area and between the rails are hollow metal paving blocks 15 contoured to fit the space. Their tops 16 are substantially flush with the heads of the rails and their side walls 17 rest upon proximate base flanges of the rails and having apertures to accommodate through bolts 18 whereby they are properly secured in place. Elements 15 form closures for the crotch area and simplify paving. 70 75

The intersecting through rails as thus assembled and metallically bound together are ready for the application of the manganese steel or other hard metal center structure for normalizing the cut down area of intersection. It is a distinct merit of my invention that the housing is a unit shell structure of inverted U or arch form. It is generally indicated by the numeral 19 and, as well apparent from Figs. 5 and 6, embodies a roof or spanning area 20 and side walls 21 having spiking flanges 22. The top of the structure is formed with a track surface or with intersecting flangeways which match the flangeways of the continuous rails. The shell or housing 19 is preferably composed of manganese steel or substantially equivalent metal having hard toughness and generally is formed by casting. The general form of the spanning structure and the fact that its side walls have a depth corresponding to the normal height of the rails, makes for ample head room or clearance between the trimmed rails and the roof of the shell and admits of permissible deflection of the structure under the 80 85 90 95 100

load which latter, obviously, is assumed entirely by the spanning structure and transmitted by it through its side arms to the foundation structure.

As shown in Fig. 5 the shell or housing center 19, when in position in the area of intersection, spans the webs of the intersecting through rails and with its side members forms grooves 23 with cut away portions of the rail flanges 24 for weld deposit metal 25 whereby the housing is metallically joined to the intersecting rails.

The metallic union of the housing with the rails is completed by weld deposit metal 26 between the ends thereof and the heads 27 of the rails, the spaced ends being formed as a V groove for the reception of the fusion metal.

It will be obvious to those skilled in the art that by my system or method I provide a strong and rigid structure that is adequately capable of taking care of heavy traffic conditions.

Having described the invention, I claim:

1. The method herein described, which consists in trimming continuous or through rails whereby they may be assembled on lines of intersection, rigidly securing them in that relation, housing the trimmed area with a wear resisting unit cast shell whose top is formed with flangeways which match the flangeways of the rails and whose sides straddle the rails and are of a depth corresponding to the normal height of the rails, welding the end terminals of the shell to the through rails by continuous or unbroken weld deposit metal, and welding the bottoms of its side members to the adjoining rail flanges by weld deposit metal extending the effective length of the side members.

2. The method herein described, which consists in trimming continuous or through rails whereby they may be assembled on lines of intersection, tying them in that relation, normalizing the area of intersection by spanning it with a frog or crossing structure comprising a one-piece casting of inverted U-form including a head having guards and flangeways matching those of the through rails and having side walls with spiking flanges, and homogenizing the assembly by welding the head to the through rails by continuous weld deposit metal which integrates the rails and also the rails and the head, and welding the side walls in the plane of their spiking flanges to the proximate base flanges of the rails.

3. The method herein described, which consists in modifying continuous or through rails whereby they may be assembled on lines of intersection, rigidly joining them by fusion welding which metallically joins the proximate base flanges and also the proximate ends of the rails, and normalizing the rails in the region of intersection by applying

ing a straddling frog or crossing structure whose top is fusion welded to the ends of the rails and whose side elements are fusion welded to the base flanges of the rails.

4. A track structure, comprising the combination of continuous or through rails assembled and united on lines of intersection, a frog or crossing spanning the area of intersection and comprising a one-piece shell of arch form whereof the head has flangeways and guards in coincidence with those of the through rails and whereof the side walls are of a depth for common support with the rails and have spiking flanges, weld deposit metal connecting the head with the through rails, and weld deposit metal connecting the side walls with the proximate base flanges of the rails.

In testimony whereof, I affix my signature.

WILLIAM G. HULBERT.
